UNITED STATES PATENT OFFICE.

BENJAMIN WEXLER, OF BROOKLYN, NEW YORK, ASSIGNOR TO THE PEELE COMPANY, A CORPORATION OF NEW YORK.

LOCKING MECHANISM FOR ELEVATOR-DOORS.

1,381,262.

Specification of Letters Patent. Patented June 14, 1921.

Application filed October 31, 1918. Serial No. 260,485.

To all whom it may concern:

Be it known that I, BENJAMIN WEXLER, a citizen of the United States, residing at the borough of Brooklyn, in the city of New York, county of Kings and State of New York, have invented certain new and useful Improvements in Locking Mechanisms for Elevator-Doors, of which the following is a specification, reference being had therein to the accompanying drawings, which form a part thereof.

My invention relates to locking mechanisms for elevator doors, and more particularly to a type thereof adapted for use upon an elevator door having slidable door sections, movable in opposite directions in the same vertical plane, wherein the locking lever passes beneath the hanger bar of the lower door section.

Locks of the character to which my invention relates are so constructed as to permit the opening of a door only when a car is at a door opening closed thereby, thus affording a factor of safety through the prevention of the opening of any door from the floor side. This construction not only prevents accidents as a result of doors being improperly opened, but also is a factor of safety in the event of fire, since it prevents the spread of fire through the shaft from one floor to another, as a result of open doors.

When the elevator is in service, the car will have an operator thereon, so that free access may be had to any floor by means of the car. When, however, the elevator service is shut down, as for the night, it is a common practice to leave the car at the top floor and leave the door upon that floor unlocked, or open, so that in an emergency, access may be had to the car.

In a lock made in accordance with my invention, the construction is such that all doors of a shaft may be positively locked, means being provided whereby the locking lever of any door may be disengaged from the hanger bar, in a manner to permit the opening of that door either for the purpose of gaining access to the elevator car, or for running a fire hose through the shaft in the event of fire.

With a lock of this character, it is essential to provide an emergency releasing

mechanism which can be actuated only by a special portable mechanism, so as to limit the use of this mechanism to the proper party, and thus prevent its use under ordinary circumstances, for the purpose of opening any door from the floor side.

A locking mechanism made in accordance with my invention, may be applied to any, or all doors of a shaft, although under normal circumstances it would be applied only to a door closing the door opening at which the car is ordinarily stopped when the elevator service is shut down.

Since the latch lever is ordinarily engaged by the hanger bar, it is essential that the emergency releasing mechanism be capable of developing sufficient power to insure the disengagement of said lever from said hanger bar.

The invention consists primarily in a locking mechanism for elevator doors, consisting of the combination with a plurality of door sections movable in opposite directions, the lower of which sections has a laterally extending hanger bar thereon, and a flexible connection therebetween, and the upper of said sections, of an oscillatory lever pivoted adjacent the side of the door within the elevator shaft, means having a normal tendency to thrust said lever toward said hanger bar, coöperating means operative upon said lever, and carried by an elevator car, whereby said lever is withdrawn from its operative relation to said hanger bar, or permitted to assume its operative relation thereto, means operative upon said lever and accessible from the floor side of the elevator door, and actuating means operative thereon, whereby said lever may be withdrawn from its operative relation to said hanger bar; and in such other novel features of construction and combination of parts, as are herein-after set forth and described, and more particularly pointed out in the claims hereto appended.

Referring to the drawings,

Figure 1 is a view of a door of an elevator shaft, broken away on horizontal planes and condensed, embodying therein a locking mechanism of my invention;

Fig. 2 is a side view of a locking mechanism, with a fragmentary portion of an elevator car in the inoperative relation thereto;

Fig. 3 is a view similar to Fig. 2, showing the locking lever released by the emergency mechanism;

Fig. 4 is an enlarged view of the upper 5 part of the latch lever in the locking relation to the hanger bar; and

Fig. 5 is a similar view, with said lever withdrawn from the operative relation to the hanger bar, by the emergency release 10 mechanism.

Like letters refer to like parts throughout the several views.

In the embodiment of my invention shown in the drawings, I have illustrated a single 15 elevator door structure of the counterbalanced type, showing a locking mechanism made in accordance with my invention, applied thereto.

This door structure comprises two sections, *a* and *b*, vertically slidable in opposite directions in the same plane. Said doors are mounted upon vertical tracks or guides *c*, upon opposite sides of the door opening, and are connected by flexible chains or cables 25 *d*, mounted upon suitably arranged pulleys *e*.

The lower door section *b* is provided with a laterally extending hanger bar *f*, projecting beyond the guides or tracks *c*, which hanger bar provides the proper offset connection for the chain or cable *d*.

When the door is opened, the section *b* in its entirety passes the sill of the door, and the section *a* passes above the lintel thereof, the proper meeting point of the doors being 35 midway between said sill and lintel.

For locking the doors in the closed position, I provide a latch lever *g* pivotally mounted upon the angle bar *h*, supporting the track or guide *c*, adjacent the side of 40 the door.

Said lever *g* is normally thrust in the path of the hanger bar *f*, means operative upon said lever and coöperating means carried by an elevator car being provided, whereby said 45 lever will be automatically removed from this position when a car is adjacent the door opening, so as to permit the opening of the door.

In the form of the invention shown in 50 the drawings, this means comprises a short secondary lever *i* also pivoted upon the bar *f*, one arm of said lever being pivotally connected with an arm of the lever *g* and the other arm thereof having adjustably 55 mounted thereon an impact member *j* adapted to be engaged by a shoe *k* carried by the elevator car *m*. Acting upon the lever *g* is a spring *n*, which spring is so set as to have a normal tendency to thrust the 60 impact member *j* into the path of the shoe *k* with a resultant oscillation of the lever *g* in a manner to bring it within the path of movement of the hanger bar *f*.

The length of the upper arm of the lever 65 *g* is such as to bring the stop surface *o*,

formed by the top of this lever, below the lower edge of the hanger bar *f*, said lever being provided with a projection *o'*, having a beveled lower face adjacent the top thereof, and presented toward the path of movement of the hanger bar *f*, forming a second stop surface a short distance below said bar, when it is in this position. The distance between the stop surfaces *o* and *o'* need not be great, it being merely necessary to afford 70 a sufficient distance to compensate for a reasonable stretch or elongation of the cable or chain *d*, or of the actuating cables of semi-automatic, or full automatic doors. 75

While a multiple stop lever is not an essential characteristic of my present invention, such a lever has certain desirable characteristics and may be used advantageously 80 in connection with other characteristics of the invention.

It is not my intention to claim this form 85 of latch lever in my present application, however.

Operative upon the lever *g* is means 90 whereby said lever may be drawn from below the hanger bar *f* from the floor side of the doors, in connection with which means I provide actuating means separable from said first named means, so as to prevent the unauthorized use of this mechanism. 95

In the form of the invention shown, I provide an opening in the wall *p* at one side of the door opening, which opening has a sleeve *q* fitted therein. Pivotedly connected with the lever *g*, adjacent the top thereof, and projecting through the sleeve, is a screw-threaded stem *r*, carrying thereon a collar *r'*, having a free sliding fit with said sleeve. The open end of the sleeve *q* is exposed upon the floor side of the wall *p*, so that the screw-threaded socket key *s*, having a flange *s'* adapted to engage the surface of the wall *p* about the sleeve *q*, or a wear plate formed by a flange upon said sleeve may operatively 100 engage the stem *r* and apply the desired stresses thereon. The key *s* has a cylindrical portion adapted to enter said sleeve and turn freely therein, said cylindrical portion being of sufficient length to engage the screw threads upon said stem. 105

The locking mechanism heretofore described, is duplicated upon opposite sides of each door, to provide a suitable support for the section *b* while it is closed, and minimize any tendency of the door to sag on one side. 110

The operation of the herein described mechanism is substantially as follows:—

Each of the doors in an elevator shaft is 115 equipped with its own independent locking mechanism, which, being arranged within the shaft, is inaccessible from the floor side of the door, so that under normal conditions all doors in a shaft are closed and locked in a manner to permit only one door to be 120 130

opened when the elevator car is at a door opening closed thereby. When a car approaches an opening, the shoe *k* carried thereby will, through its engagement with 5 the impact member *j* oscillate the lever *i*, which, by reason of its pivotal connection with the lever *g*, will impart such movement to said lever as will draw the stop surface *o* or *o'* from below the hanger bar *f*. When 10 the shoe *k* passes from its operative relation to the impact member *j*, the spring *n* will restore the lever to its normal position, where, when the doors are closed, it will pass below the hanger bar *f* and thus prevent 15 the opening of the door. By using a multiple stop lever, the locking of the door is assured even though the door sections may not be at the proper parting line.

The locking mechanism of any door in a 20 shaft, or if desired, all doors in a shaft, may be provided with an emergency release mechanism. Where a shipper cable is used, this release mechanism may be advantageously applied to all doors, since this will permit 25 access to the shipper cable in order to bring the car to the desired floor. In other types of control, however, capable of operation only from the car, it is necessary to provide only one door in a shaft with this release 30 mechanism.

In describing the mode of operation of the emergency release mechanism, reference will be had more particularly to the type of elevator control above referred to, and it will 35 be assumed that following the common practice the elevator, when service is shut down, is left upon the top floor of the building. With the ordinary hanger bar lock, it is essential that the doors either be left 40 partly open, to prevent the lever *g* becoming operative, or else to stop the car with the shoe *k* in engagement with the impact member *j*. In either case the door at the opening on this floor, is left unlocked. 45 By using a door embodying my invention, this door, like every other door in the shaft, may be closed and locked, the key *s* being carried by the watchman, so that in an emergency, he may ascend to the top floor, insert 50 the cylindrical portion of the key within the sleeve, and rotate it, so as to pick up the threads upon the stem *r*. This may be quickly done, as the collar *r'* upon said stem centers said stem with relation to the sleeve *g*, and the cylindrical portion upon the key will center the stop of the screw-threaded socket of said key. As the key is turned, it will draw the stem *r* inwardly of the sleeve *g*, the movement of which stem will oscillate 55 60 the lever *g* in a manner to draw it from below the hanger bar *f*, thus permitting the opening of the door. By the construction described, the lever will be held in this position until the key has been removed. By 65 using a screw-threaded connection between

the stem *r* and the key *s*, the power applied to the lever *g* is sufficiently great to overcome any load conditions upon the lever *g*.

By a mechanism made in accordance with my invention, an additional factor of safety 70 in the event of fire, is afforded, since all doors in a shaft may be positively locked under normal conditions, while free access may be had to the car, or to the shaft, by the watchman, or other person in possession of 75 the key. The stem *r* is inaccessible except by a special tool, so that its use to unlock a door, in the ordinary operation of a car, is impossible, although the emergency release mechanism does not in any way interfere 80 with the free operation of the latch mechanism from the car, in the usual manner.

It is not my intention to limit the invention to the precise details of construction 85 shown in the accompanying drawings, it being apparent that such may be varied without departing from the spirit and scope of the invention.

Having described the invention, what I 90 claim as new and desire to have protected by Letters Patent, is:—

1. A locking mechanism for elevator doors, consisting of the combination with a plurality of door sections movable in opposite directions, the lower of which sections has a laterally extending hanger bar thereon, and a flexible connection between said hanger bar and the upper of said sections, of an oscillatory lever pivoted within an elevator 95 shaft, adjacent the side of the door, means having a normal tendency to thrust said lever toward said hanger bar, coöperating means operative upon said lever and carried by an elevator car, whereby said lever may 100 be withdrawn from its operative relation to said hanger bar, or permitted to assume its operative relation thereto, means operative upon said lever, and accessible from the floor 105 side of the door, whereby said lever may be withdrawn from its operative relation to said hanger bar, and actuating means coöperating with said last named means.

2. A locking mechanism for elevator doors, consisting of the combination with a 115 plurality of door sections movable in opposite directions, the lower of which sections has a laterally extending hanger bar thereon, and a flexible connection between said hanger bar and the upper of said sections, of an oscillatory lever pivoted within an elevator shaft, adjacent the side of the door, means having a normal tendency to thrust 120 said lever toward said hanger bar, coöperating means operative upon said lever and carried by an elevator car, whereby said lever may be withdrawn from its operative relation to said hanger bar, or permitted to assume its operative relation thereto, a screw 125 threaded member operatively connected with 130

5 said lever and exposed upon the floor side of the door, and screw threaded means adapted to coöperate therewith, whereby said lever may be withdrawn from its operative relation to said hanger bar.

10 3. A locking mechanism for elevator doors, consisting of the combination with a plurality of door sections movable in opposite directions, the lower of which sections has a laterally extending hanger bar thereon, and a flexible connection between said hanger bar and the upper of said sections, of an oscillatory lever pivoted within an elevator shaft, adjacent the side of the door, 15 means having a normal tendency to thrust said lever toward said hanger bar; coöperating means operative upon said lever and carried by an elevator car, whereby said lever may be withdrawn from its operative 20 relation to said hanger bar, or permitted to assume its operative relation thereto, a screw threaded stem carried by said lever and projecting through an opening exposed upon the floor side of the door, and a screw- 25 threaded socket key adapted to coöperate therewith, said key being detachable with relation to said stem.

30 4. A locking mechanism for elevator doors, consisting of the combination with a plurality of door sections movable in opposite directions, the lower of which sections has a laterally extending hanger bar thereon, and a flexible connection between said hanger bar and the upper of said sections, 35 of an oscillatory lever pivoted within an elevator shaft, adjacent the side of the door, means having a normal tendency to thrust said lever toward said hanger bar, coöperating means operative upon said lever and carried by an elevator car, whereby said lever 40 may be withdrawn from its operative relation to said hanger bar, or permitted to assume its operative relation thereto, a screw threaded stem carried by said lever and projecting through an opening exposed 45 upon the floor side of the door, a screw-threaded socket key adapted to coöperate therewith, said key being detachable with relation to said stem, and means carried by 50 said stem and said key respectively, whereby said key and said stem are centered in relation to each other.

55 5. A locking mechanism for elevator doors, consisting of the combination with a plurality of door sections movable in oppo-

site directions, the lower of which sections has a laterally extending hanger bar thereon, and a flexible connection between said hanger bar and the upper of said sections, of an oscillatory lever pivoted within an elevator shaft, adjacent the side of the door, means having a normal tendency to thrust said lever toward said hanger bar, coöperating means operative upon said lever and carried by an elevator car, whereby said lever 60 may be withdrawn from its operative relation to said hanger bar, or permitted to assume its operative relation thereto, a screw threaded stem pivotally connected with said lever and projecting through an opening exposed upon the floor side of the door, a screw-threaded socket key adapted to coöperate therewith, said key being detachable with relation to said stem, and means carried by said stem and said key respectively, 65 whereby said key and said stem are centered in relation to each other.

70 6. A locking mechanism for elevator doors, consisting of the combination with a plurality of door sections movable in opposite directions, the lower of which sections has a laterally extending hanger bar thereon, and a flexible connection between said hanger bar and the upper of said sections, of an oscillatory lever pivoted within an elevator shaft, adjacent the side of the door, means having a normal tendency to thrust 75 said lever toward said hanger bar, coöperating means operative upon said lever and carried by an elevator car, whereby said lever 80 may be withdrawn from its operative relation thereto, a sleeve passing through the wall adjacent said lever, a screw threaded stem pivotally connected with said lever and projecting within said sleeve, said stem having a collar thereon whereby it is centered in said sleeve and a flanged screw-threaded socket key, having a cylindrical portion, adapted to enter said sleeve and engage said 85 stem, said key being detachable from said 90 sleeve and said stem.

95 In witness whereof, I have hereunto affixed my signature, this 21st day of October, 1918, in the presence of two subscribing witnesses.

BENJAMIN WEXLER.
